US0D1019598S

(12) **United States Design Patent** (10) **Patent No.:** **US D1,019,598 S**
(45) **Date of Patent:** **** Mar. 26, 2024**

(54) **HEADPHONE**

(71) Applicant: **SONY GROUP CORPORATION**,
Tokyo (JP)

(72) Inventors: **Fumihito Yoshikawa**, Tokyo (JP);
Koichi Sadatsuki, Tokyo (JP)

(73) Assignee: **SONY GROUP CORPORATION**,
Tokyo (JP)

(**) Term: **15 Years**

(21) Appl. No.: **29/827,080**

(22) Filed: **Feb. 17, 2022**

(30) **Foreign Application Priority Data**

Aug. 20, 2021 (JP) ..... 2021-017978 D

(51) **LOC (14) Cl.** **14-01**

(52) **U.S. Cl.**

USPC **D14/205**

(57) **CLAIM**

The ornamental design for a headphone, as shown.

DESCRIPTION

FIG. 1 is a perspective view of a headphone showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 5 Drawing Sheets
